SHINGLE

Samuel Sorber Staley, Jr., Honolulu,
Territory of Hawaii

Application October 9, 1943, Serial No. 505,672

1 Claim. (Cl. 108—8)

This invention relates to new and useful improvements in roof constructions and more particularly to an improved shingle.

An important object of the present invention is to provide a roof shingle constructed in such a manner as to facilitate laying of the shingles due to the presence of interlocking and aligning shoulders on the shingles.

Other objects and advantages of the invention will become apparent to the reader of the following description.

In the drawings:

Figure 1 represents a fragmentary top plan view of a substantial portion of a roof constructed with the improved shingles.

Figure 2 is an enlarged fragmentary detailed sectional view of a roof showing how the shingles overlap.

Figure 3 is a section taken on the line 3—3 of Figure 2.

Figure 4 is a perspective view of the lower or starting shingle.

Figure 5 is a perspective view of one of the intermediate shingles.

Referring to the drawings, wherein like numerals designate like parts, it can be seen that numeral 5 denotes the base or rafters of a roof upon which the improved shingles are laid. The present invention contemplates a starting shingle generally referred to by numeral 6 and an intermediate shingle generally referred to by numeral 7.

The starting shingle 6 consists of a rectangular-shaped plate of wood, or any other desired material, the bottom side 8 of which is flat, while the topside has one longitudinal half-portion substantially thicker than the other, this being denoted by numeral 9. The inner edge portion of this thickened part 9 of the shingle terminates abruptly to define a shoulder 10. Further, the topside of the thickened portion 9 gradually tapers upwardly as is clearly shown in Figures 3 and 4.

The intermediate shingle 7 consists of a head portion 11 tapered on both sides to a front edge 12 and from the opposite edge of this head portion 11 projects a flanged portion 13. This flanged portion 13 projects from the intermediate portion of the last-mentioned edge of the head portion 11 so as to define upper and lower shoulders 14, 15.

As can be seen in Figure 3, the starting shingle 6 at its upper edge abutting the shoulder 15, while the flange 13 not only extends over the thickened portion 9, but overhangs the shoulder 10. (See Fig. 3.)

The relation of two intermediate shingles 7 is that the blunt edge 12 engages the underlying shoulder 15 of the adjacent shingle 7, while said adjacent shingle 7 has its flange 13 resting upon the topside of the head 11 and overhanging the shoulder 14 thereof.

While the foregoing specification sets forth the invention in specific terms, it is to be understood that numerous changes in the shape, size and materials may be resorted to without departing from the spirit and scope of the invention as claimed hereinafter.

Having described the invention what is claimed as new is:

A shingle comprising a rectangular plate having the lower slightly more than one-half portion thereof of uniform thickness and the remaining upper portion of the same of gradually increased thickness from its upper edge to the lower portion, the upper portion being of the same thickness at its upper edge as that of the lower portion and being similarly increased in thickness at the top and bottom to define shoulders above and below the lower portion at the juncture of said portions, with the shoulders of the same width as the thickness of said lower portion.
